CLAIM

The ornamental design for praying hands air freshener, as shown and described.

DESCRIPTION

FIG. 1 is a perspective view of a praying hands air freshener with a suspending support cord shown in phantom lines not forming a part of the claimed invention.

FIG. 2 is a front view of the praying hands air freshener shown in FIG. 1.

FIG. 3 is a top view of the praying hands air freshener shown in FIGS. 1 and 2.

FIG. 4 is a right side view of the praying hands air freshener shown in FIGS. 1-3.

FIG. 5 is a rear view of the praying hands air freshener shown in FIGS. 1-4.

FIG. 6 is a left side view of the praying hands air freshener shown in FIGS. 1-5; and,

FIG. 7 is a bottom view of the praying hands air freshener shown in FIGS. 1-6.
